US0D1077442S

(12) **United States Design Patent** (10) **Patent No.:** **US D1,077,442 S**
(45) **Date of Patent:** **** Jun. 3, 2025**

(54) **SHOE**

(71) Applicant: **NIKE, Inc.**, Beaverton, OR (US)
(72) Inventor: **Matthew DeAlmeida**, Portland, OR (US)

(73) Assignee: **NIKE, Inc.**, Beaverton, OR (US)

(**) Term: **15 Years**

(21) Appl. No.: **29/854,375**

(22) Filed: **Sep. 23, 2022**

(51) LOC (15) Cl. **02-04**

(52) U.S. Cl.

(57) **CLAIM**

The ornamental design for a shoe as shown and described.

DESCRIPTION

FIG. 1 is a bottom view of a shoe showing my new design; FIG. 2 is a bottom front perspective view thereof;

FIG. 3 is a bottom opposite side front perspective view thereof;

FIG. 4 is a bottom opposite side rear perspective view thereof;

FIG. 5 is a bottom rear perspective view thereof;

FIG. 6 is a front view thereof; and,

FIG. 7 is a rear view thereof.

The broken line immediately adjacent to front photographic area of the toe tread pad defines the bound of the claimed design and forms no part thereof. The broken lines depicting the remainder of the shoe form no part of the claimed design.

1 Claim, 7 Drawing Sheets
